(57) **CLAIM**

We claim the design for an excavation bucket, as shown and described.

DESCRIPTION

FIG. 1 is an isometric view of an excavation bucket showing our new design;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

1 Claim, 4 Drawing Sheets

FIG. 1

FIG. 3

FIG. 2

FIG. 5

FIG. 4

FIG. 7

FIG. 6
